UNITED STATES PATENT OFFICE.

JOHN C. MUIRHEAD, OF GRUB GULCH, CALIFORNIA.

DRILL-MACHINE.

SPECIFICATION forming part of Letters Patent No. 341,813, dated May 11, 1886.

Application filed February 15, 1886. Serial No. 193,048. (No mode'.)

To all whom it may concern:

Be it known that I, JOHN C. MUIRHEAD, of Grub Gulch, Fresno county, State of California, have invented an Improvement in Drills; 5 and I hereby declare the following to be a full, clear, and exact description of the same.

My invention relates to certain improvements in drills; and it consists in the combination of devices, which will be more fully 10 explained by reference to the accompanying drawings, in which—

Figure 1 is a perspective view showing the drill and its support, together with the operating-treadle. Fig. 2 is a side elevation with 15 a section showing the rotating device. Fig. 3 is a section taken through the clamp.

A is the standard, which is fixed at any desired angle or position within the tunnel, shaft, or at any other point where work is to 20 be done, by means of a ratchet, screw, or other device for producing the proper tension. Upon this standard is clamped a plate or frame, B, from which the drill is supported as follows: C is a slide, which is dovetailed, tongued, or 25 otherwise fitted to move in corresponding grooves in the clamp-plate, and a socket is formed in this slide and in the corresponding plate, in which a beveled head, D, formed on the end of the arm E, is fitted. When the 30 clamp C is forced down in its guides upon the head D, it clamps it firmly in any position which it may occupy by means of screw-bolts or nuts F. Upon the outer end of the arm E is a journal-box or support, H, having caps I, 35 within which the journals of the ratchet J turn. The caps I may be hinged at one end, so as to be turned backward about their hinges, and may be secured by nuts or bolts at the opposite end when they are closed over 40 the journals. The ratchet and its journals are made hollow, the interior being shaped to fit the exterior of the drill, which is usually made of six or eight sided or other polygonal steel. The ratchet and journals are also made 45 in two halves, which may be separated when the caps of the box I are thrown back, so as to allow the drill to be laid in its place, after which they are put together and the caps secured over them, when the ratchet may be 50 turned, thus rotating the drill with it. By this construction any drill may easily be placed in the device with but little trouble,

and the expansion of the drill-point or the battering up of the head by the blows upon it will not interfere with the drill being introduced or taken out. 55

In order to rotate the drill and the ratchet, a movable pawl, K, is fitted to slide in a guide, L, which extends down at one side of the box H, as shown. A spring, M, is fitted 60 fixedly within this guide-box, and tends to force the pawl K upward, so that the projecting end or hook will engage a tooth of the ratchet J whenever it has been raised above the tooth. From the lower end of the shank of this pawl 65 a cord, wire, or chain, N, extends downward, and is connected with the arm or lever O, one end of which is pivoted to a clamp or arm, P, which is adjustable on the standard A. The other end of the lever O has a foot or 70 pedal, Q, upon which the operator may place his foot, thus pulling downward upon the cord N and the pawl K, and this acts to turn the ratchet J, and with it the drill, a partial revolution, the amount of turn being dependent 75 upon the number of teeth and the arrangement of the ratchet.

In order to operate this device readily, whatever angle the drill may stand at, I have fixed two anti-friction rollers, R, in the lower part 80 of the guide L, so that the cord N may work freely over these rollers when the drill is being operated in a direction not at right angles with the movement of the treadle-lever O.

By means of the arm E and the head D the 85 drill may be turned so as to operate in any position, from a vertical downward to a vertical upward.

When the miner desires to work with this drill, he strikes upon the end of it, the point 90 resting against the rock in line with the direction in which it is desired to make a drill-hole. As he strikes, he presses his foot upon the treadle Q, and thus rotates the drill slightly an instant before the blow falls upon the 95 head of it. In this manner one man can easily drill a hole which would ordinarily take two men. When drilling in an upward direction, it is necessary to hold the drill so that it will not fall back, and this is done by means of a 100 pawl, S, the point of which presses upon the side of the drill sufficiently to hold it, this pressure being caused by spring T, acting upon its opposite end. The pawl S is fulcrumed in

a sleeve or frame, U, which is fixed so as to turn loosely upon the projection of the journal which holds the ratchet, so that the drill may be turned without displacing or deranging this pawl S and its support. If the drill is being operated downward, it will be necessary to raise it slightly after the blow, in order to allow it to turn, and this may be done by a weighted arm or lever, V, having a connection with the drill by means of a sleeve, W, surrounding it, so as to bind against and lift it by the action of the weight or other suitable device, which would act as a clamp to raise the drill after each blow.

15 Having thus described my invention, what I claim as new, and desire to secure by Letters Patent, is—

1. In a drill, the supporting standard and adjustable sliding plate, which may be clamped to it at any point in its length, said plate having a semi socket or chamber to receive the lower part of the head of the drill-supporting arm, in combination with a dovetailed or channeled slide moving in corresponding guides in the plate, so as to fit over the upper portion of the head, and screws or bolts, by which it may be clamped or tightened upon said head, substantially as herein described.
2. A drill-supporting frame having an arm projecting to one side therefrom and a beveled or other suitable-shaped head at the end of the arm, in combination with a plate having a socket inclosing one half of said head and a slide chambered to inclose the other half, and moving in guides upon the first plate, together with screws or bolts, by which it may be forced down so as to clamp the head, substantially as herein described.
3. In combination with the rotary sleeve inclosing the drill-shank, and having a ratchet

formed upon its exterior surface, a pawl the shank of which moves in a guide at one side, so that the pawl will engage the ratchet, a treadle connected with the pawl-shank, so that it may be drawn downward by the action of the treadle, and a spring within the pawl-case, by which it may be returned after each depression, so as to engage another tooth in the ratchet, substantially as herein described.

4. The rotating drill-holding sleeve having a ratchet formed upon its exterior surface, the guide L, the pawl reciprocating within the guide, the operating-treadle, and a connection between the treadle and pawl, in combination with the guide-rollers R, journaled within the guide L, whereby the lower end of its pawl moves between said rollers, substantially as herein described.

5. The rotary ratchet-sleeve and the drill-shank having a longitudinal movement within it while being rotated simultaneously, in combination with the pivoted arm or pawl S, pressing against the side of the drill-shank so as to hold it and prevent its dropping when in a vertical position with the point upward, substantially as herein described.

6. The drill-shank and the inclosing-sleeve by which it is rotated, in combination with a binding-ring surrounding the drill-shank and a weighted arm or lever, Y, pivoted to said ring, and having a fulcrum or a projection from the drill-frame, whereby the drill is raised after each blow when the point is downward, substantially as herein described.

In witness whereof I have hereunto set my hand.

JOHN C. MUIRHEAD.
